UNITED STATES PATENT OFFICE

1,988,281

SHOE MAKING METHOD

Fred Maccarone, Brooklyn, N. Y.

Application May 15, 1933, Serial No. 671,109

5 Claims. (Cl. 12—146)

My invention relates to shoe making and a principal object of my invention is to provide an improved and simplified method of making shoes of the type originally taught in my United

5 States Patent No. 1,569,823, wherein an insole, to which the upper is affixed, includes an integral heel portion, a shank portion and a ball portion having a central opening therein defining a continuous marginal rand extending from the front of one side of the shank around the toe and to the front of the opposite side of the shank to afford means for initially affixing the upper to the insole, and an outsole is provided having a marginal depression conforming to the rand for receiving the same with the upper attached thereto, whereby the central portion of the inner face of the outsole is disposed flush with the upper surface of the rand.

Referring to the drawings:

20 Figure 1 is a plan view of the female portion of a die employed to centrally depress the ball portion of the rounded sole which is shown lying thereon.

25 Figure 2 is a cross sectional view taken on lines 2—2 of Figure 1 and illustrates, on a larger scale, the ball portion of the sole depressed between the male and female die portions.

30 Figure 3 is a longitudinal sectional view illustrating the method by which the rounded sole is split to provide the complementary outsole and insole portions.

35 Figure 4 is a longitudinal section thru the insole portion.

40 Figure 5 is a longitudinal section thru the outsole portion.

45 Figure 6 is a longitudinal section thru the backing piece employed to support and reinforce the sole during the splitting operation illustrated in Figure 3.

50 Figure 7 is an inverted plan view of the insole with the upper lasted and secured thereto.

Figure 8 is a longitudinal section taken thru the insole and portions of the attached upper.

55 Figure 9 is a longitudinal section illustrating the ball tread portion of the shoe with the outsole assembled thereto, and

60 Figure 10 is a side elevation of a completed shoe, shown partly in section to reveal the finished relationship of the sole portions.

In carrying out my present invention I first provide a full rounded sole 30 and then inflex or depress the central ball tread portion thereof a distance somewhat greater than the thickness of an insole to be removed therefrom. This I ac-

complish by pressing the sole between the male and female elements, 33 and 34 respectively, of a swage or pressing die, as illustrated in Figure 7.

5 After removal from the pressing die, the sole is reenforced by a perforate backing strip 36 (see Figure 6), which is formed to complement the depressed portion of the sole and is preferably made of a durable and somewhat flexible composition material. The sole thus backed up, is then passed between the rollers 37—37 of a conventional leather splitting machine, the splitting blade 38 of which is positioned to cut above the bottom of the depressed area 35, so that when the sole has been split its full length, an insole 10 portion 39, perforate centrally of its ball tread portion, and an outsole portion 40, is provided.

15 The insole 39, formed as above and trimmed to proper size, comprises an integral heel portion, a shank portion and a ball portion, the said ball portion having a central opening therein defining a continuous marginal rand 39' extending from the front of one side of the shank around the toe and to the front of the opposite side of the shank.

20 The insole 39 is next lasted to the upper 42 of the shoe to which it is secured by any of such special adhesives as are well-known in this art, or by other suitable means, preliminary to which a patch 43 may be removably pasted to cover the 25 perforate portion of the insole.

25 The outsole 40 is then placed in position over the lasted insole and the depressed portion 35 thereof is forced back into its original normal condition, as illustrated in Figure 9. In this manner a marginal depression 40' is defined on the inner side of the outsole which conforms to the rand 39' and receives the same with the upper attached thereto, whereby the central portion 35 of the inner face of the outsole is disposed flush with the upper surface of the rand.

30 The remaining steps necessary to complete the shoe are the usual ones consisting in removing the patch 43, assembling the sole lining 50 and affixing a heel 51.

35 Although I have described the outsole as being assembled in its original relation to the insole, it is obvious that the overlasted portions of the upper are interposed between the sole layers at their margins. Also it is an advantage of my improved method in quantity production that the sole portions are so accurately formed they may be freely interchanged, if desired, with others of the same size and style, an insole split from one outsole fitting satisfactorily with an-

other outsole from which a similar insole has been split.

Many modifications in the method and means here taught will become apparent from this disclosure to those skilled in the art to which this invention relates and I desire, therefore, to have the foregoing considered merely illustrative of my invention as defined in the here appended claims:

10. I claim:

1. In shoe making methods, that improvement which includes rounding a full sole from suitable material and depressing a central area of the ball portion thereof, then splitting the sole above the depressed area to obtain an insole therefrom, lasting a shoe upper to the insole in secured relation, replacing the sole in its original relation to the insole and restoring it to its normal undepressed condition; the outsole thus provided having a ball portion centrally elevated in thickness and the insole thus obtained having an opening in the ball portion thereof to receive the elevated portion of the outsole.

2. In shoe making methods, that improvement which includes rounding a full sole from suitable material; temporarily depressing a central area of the ball portion thereof; then, while the sole is thus depressed, continuously splitting the sole above the depressed area to obtain a perforate insole therefrom; lasting a shoe upper to the insole in secured relation, and replacing said sole in its original relation to the insole and securing it thereto.

3. In shoe making methods, that improvement which includes: providing a full rounded sole blank from suitable material; temporarily de-

pressing the blank over a central area of the ball portion thereof; then, while the blank is thus depressed, continuously splitting the blank above the depressed area to remove therefrom a full insole having an opening therein defining a continuous marginal rand, said rand extending from the front of one side of the shank around the toe to the front of the opposite side of the shank and affording means for affixing an upper to the insole, and the remaining part of said blank comprising an outsole unreduced in thickness over an area complementary to the opening in the insole.

4. In shoe making methods, that improvement which includes rounding a full sole from suitable material and depressing a central area of the ball portion thereof, then splitting the sole above the depressed area to obtain a perforate insole therefrom, lasting a shoe upper to the insole in secured relation, replacing the sole in its original relation to the insole and securing it thereto, and restoring the sole to its normal undepressed condition.

5. In shoe making methods, that improvement which includes rounding a full sole from suitable material; temporarily depressing a central area of the ball portion thereof; then, while the sole is thus depressed, continuously splitting the sole above the depressed area to provide an outsole having a ball portion centrally elevated in thickness and an insole having an opening in the ball portion thereof complementary to said outsole elevation; lasting a shoe upper to the insole in secured relation; and securing an outsole thus formed to said insole and to the overlasted portions of the upper.

FRED MACCARONE.
